UNITED STATES PATENT OFFICE.

JOSEPH G. FOURNIER, OF CHISHOLM, MAINE.

RAILWAY-SWITCH.

1,071,040.

Specification of Letters Patent. Patented Aug. 26, 1913.

Application filed June 19, 1912. Serial No. 704,241.

To all whom it may concern:

Be it known that I, JOSEPH G. FOURNIER, a citizen of the United States, residing at Chisholm, in the county of Franklin and 5 State of Maine, have invented certain new and useful Improvements in Railway-Switches; and I do hereby declare the following to be a full, clear, and exact description of the invention, such as will enable 10 others skilled in the art to which it appertains to make and use the same, reference being had to the accompanying drawings, and to the letters and figures of reference marked thereon, which form a part of this 15 specification.

This invention relates to certain new and useful improvements in railway switches and it has for its object the provision of switch operating mechanism so disposed as 20 to permit the setting of the switch by the raising of the switch rail from a point below the track level instead of moving the rail laterally as has heretofore been the common practice.

An essential object of the invention resides in the construction whereby the raising and lowering of the switch rail is accomplished and in the switch-operating mechanism employed to accomplish the setting 30 of the switch.

A substantial advantage derived by the raising and lowering of the switch rail over the switch-operating mechanism heretofore employed, whereby the setting of the switch 35 is accomplished by a horizontal movement of the switch rail, will at once be evident as the vertical movement of the rail will obviate entirely the difficulties heretofore experienced during the winter season occasioned by the formation of ice and snow which accumulates upon the surface over 40 which the switch rail is forced in the setting of the switch.

Other advantages will hereinafter appear. 45 To these ends and to such others as the invention may pertain, the same consists in the novel construction of the switch operating apparatus and in the manner in which the switch rails are disposed relative to the 50 track rails, all as will be more fully herein-after described, shown in the accompanying drawings and then specifically defined in the appended claims.

The invention is clearly illustrated in the 55 accompanying drawings which, with the nu-

merals of reference marked thereon, form a part of this specification and in which:—

Figure 1 is a plan view of a railway switch embodying my invention. Fig. 2 is a sectional view upon the line 2—2 of Fig. 60 1. Fig. 3 is a cross sectional view on line 3—3 of Fig. 1. Fig. 4 is a cross section upon the line 4—4 of Fig. 1. Fig. 5 is a side elevation of one of the cross ties. Figs. 6 and 7 are detail views of the rail, and 65 Figs. 8 and 9 are detail views of the supporting or sliding block.

Reference now being had to the details of the drawings by numerals, 1, 1 are the main rails of a railway track and 2, 2 the movable or switch rails which are designed in the present instance to be set by means of switch-operating crank or lever 3 disposed at the side of the track, the said operating lever being provided, if desired, with a suitable signal lamp 4.

5, 5 are cross ties or timbers, the end portions of which serve as supports for the main track rail. The central portions of the ties are chambered out as shown at 6, 6, 60 and journaled within suitable supports 7, 7 provided therefor is a longitudinally disposed shaft 8.

9, 9 are blocks, the lower faces of which are beveled as shown at 10, the bevel corresponding with the bevel inclined side walls 11 of the chamber 6, over which inclined surfaces the said blocks move when actuated by the switch-operating lever 3. The upper faces of the said blocks are chambered as shown at 12 to form a seat for the flange upon the face of the switch rails seated upon the block. Yokes 13 are secured to the rock shaft 8 and have pivotal connection with eyes 15 formed at the inner 65 ends of the rods 14, which in turn, are pivoted in pairs to each of said blocks 9.

16 is a connecting link pivotally connected at one of its ends with the outer end of an arm 17, the opposite end of which arm is 100 carried by the rock shaft 8, while the outer end of the link 16 is connected with the lower end of the switch-operating lever, the rotation of which lever will cause the rotation of the rock shaft.

105 The flanges of the track rails 1 are removed along that portion of the rail which contacts with the outer faces of the switch rails 2, as at 18, so that in the vertical movements imparted to the switch rails, 110

through the medium of the movable blocks 9, contact of the vertical meeting faces of the rails will be maintained. The vertical faces of the beveled switch rails are provided with beveled chambered portions 19, 20 and 21, while the straight portion of the rail is provided with rectangular chambers or recesses 22. These chambers are designed to receive the beveled portions of the blocks 10 upon which the rail is seated and serve to guide the rail in its vertical movement and securely retain the vertical face of the rail in contact with the vertical face of the track rail, while the lower face of the said switch rail, 15 provided at intervals with dowel pins or extensions 23 which move in vertical openings in the base 7 upon which the rail is seated and serve also to retain the rail in vertical alinement at all times.

20 While, for the sake of clearness, I have not shown a platform for covering the switch-operating mechanism, in practice it will be found advisable to provide a covering to protect the working mechanism of 25 the device between the tracks from ice and snow during the winter season.

From the foregoing description, the operation of the switch will be at once readily understood.

30 The rotation of the switch lever 3 will, through the mechanism interposed between it and the rock shaft 8, serve to effect a partial rotation of said shaft. The turning of the lever in one direction will serve to 35 rotate the blocks upon which the vertically movable switch rails are seated and to bring the tread of said rails into alinement with the tread of the main track rails, thus setting the switch, while a rotation of the 40 crank in the opposite direction will serve to depress the blocks and rails carried thereby, thus restoring the alinement of the track rails.

Having thus described my invention, 45 what I claim to be new and desire to secure by Letters Patent is:—

1. In a railway switch apparatus, the combination with the main and siding rails of a railway, vertically movable switch 50 points, ties upon which said rails and points are mounted, and provided with inclined

ways, a rock shaft and means for rocking the same, blocks with pivotal yoke and rod connections between the same and said rock shaft, said blocks movable upon said inclined ways of the ties and adapted to raise and lower one or the other of said switch points, projections upon said switch points, apertured plates upon the ties in which said projections are guided as the switch points 60 are raised and lowered.

2. In a railway switch apparatus, the combination with the main and siding rails of a railway, vertically movable switch points, ties upon which said rails and points 65 are mounted, and provided with inclined ways, a rock shaft and means for rocking the same, blocks with pivotal yoke and rod connections between the same and said rock shaft, said blocks movable upon said inclined ways of the ties and adapted to raise and lower one or the other of said switch points, projections upon said switch points, apertured plates upon the ties in which said 70 projections are guided as the switch points 75 are raised and lowered, the face of each switch point rail being recessed and adapted to receive the inclined ways upon said ties.

3. In a railway switch apparatus, the combination with the main and siding rails 80 of a railway, vertically movable switch points, ties upon which said rails and points are mounted, and provided with inclined ways, a rock shaft and means for rocking the same, the under surface of each block 85 being inclined and having a projection upon one edge thereof with an under cut recess in its edge for engagement with the flange of the switch point, and a horizontal portion at the upper end of the inclined block, 90 for engagement with a horizontal portion of the tie at the upper end of said inclined way, and means for rocking the shaft to raise said blocks and means for holding the same in elevated positions, as set forth. 95

In testimony whereof I hereunto affix my signature in the presence of two witnesses.

JOSEPH G. FOURNIER.
